[57] CLAIM

The ornamental design for a gazebo, as shown and described.

DESCRIPTION

FIG. 1 is a perspective view of a gazebo showing my new design;

FIG. 2 is a fragmentary front elevational view, showing one of eight, identical faces;

FIG. 3 is a fragmentary side elevational view disclosing an opposing pair of one of eight identical trusses;

FIG. 4 is a top view thereof; and,

FIG. 5 is a front half elevational view of FIG. 1, the rear half being omitted for the convenience of illustration.
